PERMUTATION-LOCKED RECEPTACLE.

1,358,672.

Specification of Letters Patent.

Patented Nov. 9, 1920.

Application filed January 29, 1917. Serial No. 145,214.

To all whom it may concern:

Be it known that we, FREDERICK W. BARNES and ERNEST C. ALLEN, citizens of the United States of America, and residing 5 in Rochester, in the county of Monroe and State of New York, have invented certain new and useful Improvements in Permutation-Locked Receptacles; and we do hereby declare the following to be a full, clear, and 10 exact description of the same, reference being had to the accompanying drawings, forming a part of this specification, and to the reference-numerals marked thereon.

Our invention relates to permutation 15 locks and more particularly to a receptacle having a closure secured thereto by a permutation lock. It has for an object the provision of a neatly appearing, simply constructed, easily assembled and inexpensive 20 receptacle for carrying coin or other articles, and an effective type of permutation lock concealed from view within the receptacle to prevent it being readily tampered with, and which comprises such simplicity 25 of design and such a small number of parts that friction and difficulty of operation is minimized and it is very easy to open the receptacle, if the combination is given. With this and other objects in view, as will 30 appear hereinafter from the following disclosure, our invention consists in the combination of parts described in the specification and covered by the claims annexed hereto.

Reference is to be had to the accompanying 35 drawings forming a part of this specification in which like characters designate like parts, and in which:

Figure 1 is a vertical elevation partly in 40 section of our receptacle with the cap separated therefrom.

Fig. 2 is a vertical elevation with the cap in place.

Fig. 3 is a section of the cap on the line 45 B—B of Fig. 1, looking in the direction of the arrows.

Fig. 4 is a plan view of a tumbler ring.

Fig. 5 is a perspective view of a locking ring fixed to the receptacle.

Fig. 6 is a plan of a washer separating 50 two tumbler rings.

Fig. 7 is a perspective view of the top retaining washer, the other washers being similarly made, although narrower.

Fig. 8 is a section of the cap on the line

A—A of Fig. 1, looking in the direction of 55 the arrows.

In the drawings we have shown a specific embodiment of our invention, involving a receptacle constituting a coin bank having a rotatable cap or cover adapted to be telescopically associated with and fastened thereto by means of our special type of permutation lock, which is concealed from view within the cap and operable by rotation of the latter, although it is obvious that this 60 type of lock can be applied to other types of receptacle and utilized for other purposes within the scope of our invention. As illustrated, the receptacle may comprise a cylindrical casing 1 of suitable material carrying 65 a cap 2 telescoping over the open end of the receptacle. A plurality of annular tumbler rings 3, separated by spacing members or washers 4, are revolvably located preferably on the upper end of the receptacle in such 70 a position as to be concealed within the cap when the latter is locked in place, although it is clear that they may be carried by either the cap or the receptacle. These rings and washers are held between a laterally extending 75 flange 5 on the upper end of the receptacle and a fixed collar 6, the flange 5 being preferably flush with the outer surfaces of the tumblers and washers. The tumbler rings 3, of which there are three in number 80 in the form illustrated, carry lugs 7, 8 and 9 projecting above the otherwise smooth surfaces of the rings and preferably in the specific embodiment of my invention, a second series of lugs 10, 11 and 12, each of 85 the latter series being diametrically opposite the other lug on its carrying ring. Fixed to the collar 6 in a non-rotative relation to the receptacle is a further member L-shaped in cross section (see Figs. 1 and 5) comprising 90 a laterally extending ring 13 engaging collar 6 and an upwardly extending flange 14 spaced from said collar 6 to allow insertion of the lower edge of the cap 2, when the tumbler rings are properly positioned, into 95 the groove formed thereby to conceal said lower edge of the cap. The fixed member 14 is provided with inwardly projecting lugs 15 and 16 suitably spaced apart to form an 100 additional locking means.

The lugs 7, 8, 9, 10, 11 and 12, on the tumbler rings are adapted to coöperate with rings or annular shoulders on the inside of

cap 2 to retain the latter in position and thereby lock the receptacle. These inwardly projecting shoulders 17 within the cap are suitably spaced apart to allow the lugs on the tumbler rings to fit and rotate therebetween. The height of the lugs on the tumbler rings correspond with the depth of the grooves between the shoulders 17, and the inner diameter of the cap is such that the shoulders 17 project inwardly between the lugs on the tumbler rings when the cap is in place, so that except in the unlocked position of tumbler lugs the removal of the cap may be prevented by the engagement of the tumbler lugs and the annular shoulders 17. The lugs 15 and 16 on the ring 14 similarly ride within a groove 18 on the outside of the cap and engage the outwardly extending annular shoulder 19, to aid in preventing removal of the cap.

In order that the cap may be removed or placed in position for locking, it is necessary to provide grooves or channels 20 and 21 whereby the lugs on the tumblers may be withdrawn from between the shoulders 17. To accomplish this, we cut away portions transversely of the shoulders 17, as illustrated in Figs. 1, 3 and 8, in alinement with each other to form such channels, so that when the lugs on the tumbler rings are in alinement they may be withdrawn through these cut away portions. Similarly a portion is cut out at 22 to allow withdrawal of the lug 15, which in this form of device is not positioned diametrically opposite the lug 16. The latter lug 16 is withdrawable through the slot through which one series of lugs on the tumbler rings is withdrawn. It will accordingly be seen that to remove the cap or put it on, it is necessary that one series of lugs on the tumbler rings be positioned in alinement with the lug 16, the other lugs on the rings being also in alinement. Then, if the proper channels in the cap are opposite the right set of lugs, the cap may be withdrawn or put in place.

When the cap is in place and the tumbler rings have been so rotated that the lugs are not in alinement, means must be provided for moving or setting the tumbler rings into the unlocked position, since these are concealed beneath the cap and are not directly manually operable. To accomplish this purpose, we provide on the inside of the cap in the grooves between the retaining shoulders 17 certain operating lugs 23, 24 and 25 on one side of the channel 21, and 26, and 27 on the other side. These operating lugs are each of such size and so positioned as to be adapted to engage the locking lugs on the tumbler rings. When the cap is rotated back and forth relative to the casing to certain predetermined positions, the operating lugs engage the locking lugs and successively move the latter to their positions

of alinement, permitting removal of the cap. By this construction, we provide a separate operating means for each tumbler ring, thus minimizing friction and eliminating certain difficulties present where it is necessary for one ring to drive an adjoining ring and the force acting on the last ring is applied through all the remaining rings in the series. Furthermore, by having each tumbler ring operated by a separate lug and all the operating lugs carried and moved by the cap, the design is made extremely simple and economical of manufacture and assemblage, and no complicated parts liable to get out of order are interposed between the manually operated part and the tumbler. The tumbler lugs 7, 8, 9, 10, 11 and 12 perform the double function of interlocking with shoulders 17 and co-acting with lugs 23, 24 and 25 on the cap during the setting of the tumblers.

In order to conceal the channels 20 and 21, which in the structure illustrated, are formed by cutting entirely through the material of the cap where the shoulders project, we preferably provide a covering 29 thereover. This covering 29, which may be of paper or similar material, gives the cap a smooth outward appearance, and at the same time conceals the outside of the stamped grooves forming the inner projecting shoulder 17 and hiding the position of the operating lugs stamped in the cap. This covering 29 readily receives the numerals shown in Fig. 2 for indicating the combination of the lock. For the insertion of coins a slot 30, preferably sloping downwardly is provided near the lower end of the receptacle. A resilient member or spring 31 is fixed to the bottom of the receptacle in such position as to thrust the coin upwardly once it has been inserted through the slot, where it cannot again be withdrawn through the entrance opening. For convenience in determining the amount of coin in the bank, observation openings 32 are provided in the exterior thereof.

In the specific form illustrated, the combination is such that when the cap is rotated at least one complete revolution in the direction of the ascending numerals, as illustrated in Fig. 2, relative to the fixed pointer 28 and stopped at numeral 14, then rotated in a reversed direction to the numeral 34, then forwardly to numeral 6 and then back to numeral 4, the operating lugs within the cap engage the tumbler rings and move them all at first and then successively position them independently of each other, where the locking lugs thereon are in alinement with locking lug 16 and in line with channel 21 formed by the cut away portions of shoulder 17 within the cap, whereupon the cap may be removed. To put the cap on and lock the receptacle, it is necessary to

have the lugs in the same position as when the cap is removed and the pointer 28 opposite numeral 4 on the cap.

By this construction we have provided a simplified form of permutation lock in which the locking tumbler rings are concealed from view and each is rotated independently of and without engaging its companion rings by a single rotative member 10 having a plurality of independent means associated therewith for acting separately on the tumblers. Each of the lugs on the tumbler rings is actuated by its own individual operating means on the cap. Moreover during the successive movements of the cap when the tumblers are being brought into unlocking position, the cap and its actuating lugs move in the same operative plane, no axial movement of the cap or actuating 15 means being necessary to manipulate the tumblers. In this type of lock it is necessary to have but a single series of indicating numerals, thereby avoiding considerable confusion in operating the mechanism. Furthermore, in the construction of a small coin bank it is possible to stamp out most of the parts from metal blanks, it being especially noticeable that the cap formed of a single piece, involves not only the closure 20 for the receptacle, but also a series of retaining rings or shoulders coöperating with the lugs on the tumbler rings and operating means for rotating the tumblers. Similarly the tumbler rings, their spacing washers and the retaining ring 6 and the fixed ring 14 may be stamped out in a simple fashion and slid into position, in the construction illustrated, over the body of the receptacle, thereby making assemblage of the device 25 simple and quite economical.

It is furthermore to be noted that the covering 29, bearing the scale or series of designating characters, may be adjusted to any desired position on the cap, so that the combination of the lock may be changed. In the construction herein described, the paper covering 29 may be removed and replaced in a new position, and if desired sealed in place by any suitable adhesive, although it is obvious that various means for adjusting this covering 29 or fastening it in place may be adopted. If the covering is shifted relative to the operating lugs within the cap so that, when the tumbler rings are in alinement and the cap is removable, the pointer 28 constituting an index mark is opposite the numeral 2 instead of 4 as described above, then the new combination will vary by two points from the old one in each of its combination 30 numbers. It, therefore, is within the scope of our invention to provide a member carrying a portion of the coördinated designating marks of a scale and index, which may be adjusted in position relative to the cap and 35 its operating means for moving the tum-

bler rings, so as to give different combinations for the lock.

Having thus described our invention, what we claim as new and desire to secure by Letters Patent is:

1. In combination with a receptacle having a body rotatably associated with a removable cap, tumbler rings provided with lugs and movably supported on one of said parts and shoulders on the other of said parts adapted to engage said lugs and lock the parts together, said part having the shoulders also being provided with a lug for each tumbler ring adapted when rotated to move into engagement with the tumbler ring lug and rotate the ring to a desired position.

2. The combination with a receptacle having a removable cap therefor, of locking means adapted to hold said parts together, comprising a plurality of tumblers rotatively mounted on said receptacle and constituting one element of the lock, means in the cap to engage said rings and form the complementary element of said lock and a plurality of separate means associated with said cap and simultaneously moved thereby to operate said tumblers independently of one another, and to move them to an unlocking position.

3. In a receptacle the combination of two relatively revoluble, telescoping, detachably associated box members, a plurality of tumbler rings carried by one member, rotatable independently of one another, a locking lug on each of said rings, shoulders on the other member, each adapted to engage a lug on a ring to retain the box members in locked relation, and operating lugs adjacent said shoulders adapted to be moved into engagement with said tumbler lugs to move the rings into unlocking position, said shoulders terminating at points in longitudinal alinement to form a passageway permitting removal of the tumbler lugs past said shoulders when alined opposite said passageway.

4. In combination with a receptacle, a removable, rotatable, telescoping cap therefor, tumbler rings carried on said receptacle and concealed beneath said cap, a lug on each of said rings, annular shoulders within said cap normally engaging said lugs to lock the cap on the receptacle, said shoulders having a passageway therethrough, and operating lugs between said shoulders on the cap 115 adapted to rotate said rings independently of one another to bring said tumbler lugs into alinement for removal through said passageway.

5. In a receptacle comprising a body and a telescoping cap rotatably associated therewith, tumbler rings rotatably carried on said body beneath said cap, each of said rings having a lug thereon, locking shoulders within said cap adapted to be engaged by 130

said lugs to hold the cap in place, said shoulders having a groove transversely cut there-through to permit passage of said lugs, and lugs on said cap between said shoulders 5 adapted to engage the lugs on the rings and rotate the latter upon turning movement of the cap whereby the tumbler lugs may be alined for removal through said groove.

6. In a receptacle comprising a body and 10 a telescoping cap rotatably associated therewith, tumbler rings rotatably carried on said body beneath said cap, each of said rings having a lug thereon, inner locking shoulders within the cap adapted to be engaged 15 by said lugs to hold the cap in place, a fixed lug on the body coöperating with an outer shoulder on the cap serving as an auxiliary locking means, a groove cutting said inner shoulder transversely through which the 20 tumbler lugs may be removed when in alignment, a groove through said outer shoulder so located that, when the cap and tumbler rings are correctly positioned for removal of the inner lugs through the groove in the 25 cap, said fixed lug may slide through the groove in the outer shoulder on the cap and lugs within said cap between the inner shoulders adapted to engage the tumbler lugs and rotate the latter when the cap is 30 turned.

7. In combination with a receptacle having an index mark thereon, a plurality of tumbler rings rotatably carried by said receptacle, a rotatable cap for the receptacle 35 over said rings, means associated with said cap adapted to coöperate with the rings to lock the cap on the receptacle, operating lugs

within the cap adapted to engage said rings and rotate them to an unlocking position upon turning the cap and a scale member 40 bearing a series of designating characters, adjustably located on said cap, whereby the combination of the lock may be changed by shifting the location of said scale member relative to said cap and index mark on the 45 receptacle.

8. A permutation lock comprising two parts to be locked together, a plurality of tumblers carried by one part, each tumbler including a locking element, devices on the 50 other part for interlocking with said elements, and means on said other part for setting said tumblers by movably engaging said elements, whereby said elements function doubly in locking and setting. 55

9. A permutation lock comprising two parts to be locked together, a plurality of independent tumbler rings carried by one part, each ring including a lug, shoulders on the other part for interlocking with said 60 lugs, and operating lugs on said other member for setting said tumbler rings by movably engaging said tumbler lugs, whereby said tumbler lugs function doubly in locking and setting. 65

In testimony whereof, we have signed this specification in the presence of two witnesses this 26 day of January, 1917, at Rochester, N. Y.
